(57) **CLAIM**

The ornamental design for a detachable part for electronic device, as shown and described.

DESCRIPTION

FIG. 1 is a front, top and left side perspective view of a detachable part for electronic device showing my new design; FIG. 2 is a front, bottom and right side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view thereof, in an environment of use, in which the detachable part for electronic device is a housing element of a video game console.

The broken lines shown are included for the purpose of illustrating the unclaimed portions of the detachable part for electronic device and form no part of the claimed design.
